R. S. BROWN

CLOSURE FOR BOTTLES, TINS, JARS, CONTAINERS, AND RECEPTACLES

Filed Nov. 1, 1921

INVENTOR:
Robert Stanley Brown
By Wm Wallace White
ATTY.

UNITED STATES PATENT OFFICE.

ROBERT STANLEY BROWN, OF LONDON, ENGLAND.

CLOSURE FOR BOTTLES, TINS, JARS, CONTAINERS, AND RECEPTACLES.

Application filed November 1, 1921. Serial No. 512,154.

To all whom it may concern:

Be it known that I, ROBERT STANLEY BROWN, of 39, Victoria Street, London, S. W., England, a subject of the King of Great Britain and Ireland, have invented certain new and useful Improvements in and Relating to Closures for Bottles, Tins, Jars, Containers, and Receptacles, of which the following is a specification.

10 Wherever I herein use or refer to any of the four words: lid, lids, lid's lids', I refer to and include any and all herein (as well as now) mentioned or described caps, lids, capsules, covers and the like and any of their kinds.

Wherever I herein use or refer to any of the four words: receptacle, receptacles, receptacle's, receptacles', I refer to and include any and all herein (as well as now) mentioned or described bottles, tins, jars, containers and receptacles and any of their kinds.

Wherever I herein use or refer to any of the four words: rim, rims, rim's, rims', I refer to and include any and all herein (as well as now) mentioned or described rims, dependent flanging, skirting, bands, or rim-like formations, and any of their kinds, whether integral or non-integral with a lid, used in any suitable manner in one piece or suitably joined pieces, or interruptedly formed.

Wherever I herein use or refer to any of the four words: lock, locks, lock's, locks', I refer to and include any one (or any greater number) of any and all of the herein mentioned or described manners, forms, types, and classes of rim provisions (and rim attachments and means) whereby a rim engages a receptacle (or its attachment or attachments) to obtain a hold thereon.

Wherever I herein use or refer to any of the four pairs of conjointly used words: receptacle's grip, receptacle's grips, receptacle's grip's, receptacle's grips', I refer to and include any one (or greater number) of any and all of the herein described, or stated receptacles' portions or provisions for engaging the said lock or locks.

50 The invention relates to means for closing receptacles with a lid or cover provided with a rim whose locks are adapted to be applied to engage suitably disposed receptacle's grips; sealing media, or medium, or

packing being interposed and compressed 55 between the receptacle and lid or rim, by either (or both) of the latter in any substantially firm manner, the said rim being so formed that external pressure applied to its periphery deforms it in a manner so as 60 to cause its lock or locks to move substantially disengagingly clear of the receptacle and thus become disengaged, and preferably for frequent on and off use, which use 65 the invention obviously suits.

This invention mainly relates to rims, of innumerable shapings, being for example applicable to inkwells, pepperettes, holed lids, (with or without hinging or like provision), in fact to any closure rim formation 70 or flanging capable of use with a receptacle shaped externally in the immediate vicinity of its orifice in accordance with the requirements apparent from the following description, whether such vicinity be oval, 75 round, rectangular, or other geometrical or irregular shape.

I use a receptacle which has in one or more suitable positions any indentations or 80 projections or shaping or provision which would obviously provide a receptacle grip (for rim locks) of the nature already herein set forth, as, for example, external:—grooving, flanging, beading, recessing, 85 bosses, folds, seams, corrugations, false or full wiring, or combinations thereof, (roughened if desired), selected and shaped as suits the receptacle's construction or material.

I may use any suitable sealing medium, 90 media, or packing, in ring, disc, laminated, or any other suitable form, shape, or cross section, whether loose, held by adhesion, or any other suitable means, in varying position, and whether placed, folded, crimped, seamed, or applied in plastic or fluid or solid condition into any suitable grooving or any other suitable position in (or on) the lid, rim, or (or as well as) the receptacle. For example I may use cork, fibre, paper, papier mâché, though for most purposes I prefer to use dependably impervious material, such as rubber, balata, rubber compositions, impregnated cork (or paper), and dispose sealing media between the lid 100 and rim and the receptacle.

To carry this invention into effect, a lid or rim is so shaped with respect to its mating

receptacle that when in an "on" position, one or more "clearance" portions of the rim in any suitable position and manner are caused to be sufficiently far away from the receptacle's external periphery that external pressure applied to the rim in the neighbourhood of the said portion or portions (by hand or suitable appliance) can cause the rim's material to yield inwardly with resulting alteration of the rim's contour (as well as thereby unsealing a vacuum closure if so desired, as a pronounced lifting action of the rim usually occurs). A dominant feature of this invention is that I practically ignore in lock design and the closure's general arrangement the making of provision or allowance for such lifting action to occur thus obtaining a rim of customary economical depth though obviously I can and may make such provision and am aware of its releasing value with some forms of locks. The rim is made of suitably springy material, and with sufficient degree of continuity that in consequence of the said inward yield, other portion or portions of the rim's periphery will tend to recede from the receptacle; and the locality of these latter "receding" portions is where I arrange a rim lock or locks to engage with receptacle's grip or grips, in order that the rim's recession here may free such engagement to substantially a fully disengaged extent. To obtain these said clearance portions (or positions) I may use any suitable means, as for example:—all round rim edge clearance, by forming bulges outwardly (or inwardly or both) on the rim, or by providing the receptacle with one or more recessed or raised portions where the rim covers it. The latter suitably disposed may restrain the rim from transit disturbances and assist in controlling the extent of the said recession action and more especially if such portions have vertical narrow channelling in which the rim edge rides (or nests).

I may therefore in some receptacles for preventing transit disturbances apply the rim so that it has to be rotated to reach its operative clearance position for release, or to meet one or more suitably disposed receptacle excrescences intended to impart releasing pressure frictionally to the rim's exterior clearance portion (or interior against the rim lock). Alternatively I may use a guard rim having indents which on rotation of the guard rim similarly apply frictional rim releasing pressure.

Hereafter I use the following numbers as a reference to the features or conditions they indicate. This invention may be used for closures of (1) hermetic, . . . (2) pressure resisting, (3) hermetic vacuum, . . . (4) automatic vacuum types; each with (5) such regulatable automatically re-seating safety valve action as is desired; and by this inven-

tion's constructions and application method, excepting where I state otherwise, the foregoing five closures can:—

(6) fulfil their duties without damage or permanent displacement of locks, 70

(7) have sealing (and resealing) compression applied and retained to any desired degree, (and beyond atmospheric pressure).

(8) be re-applied in the true original, or a new, or more than one, "on" position on 75 the receptacle, taking up variations in sealing media,

(9) optionally—entail initial destructible removal to prevent fraud,

(10) be instantly and frequently re-applied by "springing on," and instantly removed by either pressing on or squeezing the rim at its clearance position (or positions), 80

(11) have the positions stated in clause 85 (10) very closely defined and not diametrically opposite, thus assisting feature (14),

(12) ensure less risk than heretofore of receptacle damage when applying despite their usual inaccuracies,

(13) be applied without turning the lid, 90 thus preventing disturbance or injury of sealing media,

(14) resist transit disturbance better than any known instantly removed and re-applied lid, 95

(15) be adapted to retain sealing media when a lid is removed,

(16) have exceptionally liberal amount of locking or pressure locking hold without interference with its "on" and "off" features, 100

(17) automatically tend to draw the locks inwards as the internal receptacle pressure rises,

(18) retain indefinitely cold pressures, 105 and without structural alteration still relates (if so desired) identical pressures under high internal temperatures,

(19) automatically adapt itself to the many processing methods used for foods, 110 and whether wholly or partially cooked in the receptacle after closing,

(20) be applied to most existing receptacles either with or without tools, or having to register the rim rotationally to the receptacle, 115

(21) be made in one press tool operation,

(22) fulfil such conditions as I mention economically, without deeper or thicker rims than is usual. 120

Four noticeable and usual features which I have discovered and make use of in this invention (proved by my exhaustive tests and research) are:—

(23) that rim release as described is not materially prejudiced by having to hold and meet the opposing reaction against such release of light or heavy compression of a sealing medium directly interposed between the lid (or rim) and the receptacle, 125

(24) that such release as at (23) is possible on both shallow and deep rims,

(25) that by numerous constructional variations I can control and direct, and augment, and graduate pressure of release and resulting movement of the locks, and in combination with (23) and (24), and without having to adopt uneconomical thickness of closure material to effect these features, or to use extra metal in forming large rim pressing formations which may imperil feature 14,

(26) that thin gauge closure material constructed in accordance with this invention gives a powerful closure, and with well defined "on" positions or position.

I may use a rim (or lid) or receptacle of the kind having therein, or thereon, or attached thereto, any suitable of the innumerable obvious forms of suitably disposed engagements or engaging members (or provision) applicable to this invention (and its distortion manner of release) to serve respectively as locks or receptacle's grips.

Such suitable engagements (or engaging members) could be for example of like types to the following:—snap on, snap in, indentations into recesses, pips, hooks, bosses, claws, shouldering types, thread or bayonet like, tongues and scallops; making no claim, however, to any of those known closures, combinations having thread-like engagement adapted solely to rotational removal. In further describing suitable locking arrangements I wish it to be understood the form of my proposed locks are in most instances of commonly known patterns, and further that it is not novel (in fact, proprietary) to provide for example, a rounded bead at the

lower edge of a cap's flange flattened at intervals to provide locking projections, as also to so curl a cover's free edge as to lie enveloped within such coil and collapsing the latter at intervals to provide instruck locking projections, as also such enveloped edge construction in certain other combinations with locking projections and other indented constructions, as for example inventions such as fully described in specification Nos.

50 13,973/15 and 1,079,238.

In order to collectively meet features hereinbefore numbered 1, 2, 3, 4, 5, 6, 7, 8, 10, 14, 18, 19, 22, 26, and in any combination, the design of the rim's locks in combination with this invention is a fundamental underlying feature, and actual yield in the lock itself research proves unnecessary, and I therefore strongly prefer to employ rim locks (hereinafter called dependable rim locks) of any suitable one or more (or suitable combination of) the following types:—flanging, channelling, seaming, (partial or full) false or solid wiring, folds, crimping, slots, grooving, clusters of closely pitched indentations, optionally additionally corrugating or crimping or roughening any suitable of these for further strength or grip, and optionally (before or after or both before or after a receptacle's processing or filling) employing rim denture tools to force

70 suitable of these dependable lock formations or suitable others at any desirable position (pre-formed if so desired) on or into engagement with one or more suitably disposed receptacle's grips. Most of these dependable locks embody feature 21. Another type of dependable lock I prefer is an upturned internal rim edging, optionally crimped or corrugated.

75 A closure for features 4, 5, 6, 18, 19 in this invention is constructively proportioned as though the receptacle's internal pressure was a load and the lid or rim the load support, whose span (lock spacing), strength, and stiffness have been scientifically proportioned by static considerations and conditions to get a recoverable specific deflection of the lid or rim between the locks to obtain pressure release under such load with due compensation for (and consideration of) the following factors (when present):—the extent to which the sealing medium is compressed to allow for receptacle inaccuracies together with its initial and ultimate sealing compression desired; temperatures' expansion effects; processing time, temperature, and method; the recoverable yield, spring, and strength properties of the lock.

80 I can obtain all the stated 26 features without having to necessarily resort to lid and rim strengthening or weakening formations of a nature now to be described, but such formations produce a closure incomparably better as regards features 2, 3, 4, 5, 6, 7, 11, 14, 16, 17, 18, 19, 22, 23, 24, 25 and 26. Such formations are ones which locally and preferentially (or as well as generally) provide rigidity (or reduced rigidity) at varying portions of the lid or rim (or both). I may use any suitable such formations, as for example any suitable one or more or combination of the said dependable lock formations, (or recesses, dishings, holes, cuts, scallops), some obviously suitable to a rim edge, others obviously applicable to any portion of a lid's top, rim, or both.

85 Wherever I herein refer to strengthening or stiffening or weakening a rim, or lid, or lid's top, or rim's edge for any purpose I may use any suitable of such formations in any number, and in any suitable manner, as these stated and other equivalent ones are used universally in the working of sheet metal for such purposes and in countless forms and combinations and variations such as:—shape outlines, length, height, depth, position, contour, and in many directions such as:—straight, waved, curved, spiral, angular, sinuous and combinations of these.

90 95 100 105 110 115 120 125 130 To better obtain features 4, 5, 17, 18, 19,

22, (complying if desired with feature 21) I may use any suitable lid top or rim strengthening or weakening formation as above described, a few of such being later described in the reference to the drawings herewith. Corrugating the rim's periphery at the lock portions appreciably strengthens the rim at these parts, while scalloping or relieving or reducing the rim's metal between the locks provides further yield at these latter places. Similarly, and for like features, corrugations or dishings may be suitably disposed on the lid top to coact with the rim and rim's formations.

15 In like manner as described in the last three paragraphs further use is made of weakening and strengthening formations for perfecting features 11, and 25 (and consequently features 10, 14, and 16). For example:—stiffening the clearance portions of the rim, makes them offer more resistance, and prevents permanent deflection of the rim (or its bulge) thus permitting of a small bulge with consequent metal saving, and more effective release, as when such portions are pressed inwardly their yield towards the centre line of the receptacle tends to lessen and the yield of the rim consequently tending to increase towards the locks. I further perfect these features (with still further economy of material) by directing the releasing motion (due to rim squeezing or pressure) definitely towards a specific direction (or lock) by strengthening locally those portions of the rim where I do not want the latter motion to occur (or weakening the positions where I do, or both of such means); one simple method being to use both long and short locks optionally combined with rim bulges which (preferably) gradually merge into the normal rim's periphery at the short lock. Such constructions are exceptionally valuable when applied to slip lids and friction holding locks, since strengthening and weakening formations of the types described produce a strongly gripping slip lid which can deform appreciably without similarly deforming springy receptacles (thus avoiding a prejudicial clinging action), and further perfects this type of lid in features 10, 11, 13, 14, 15, 16, 20, 21, 22, 23, 24, (25 last section) and more so still when used with other means herein stated for preventing accidental disturbance.

For feature 14 rims may be made so difficult to release (or apply) as to require mechanical advantage appliances to supply the necessary releasing deformation pressure thereto, and I may use any such suitable appliances as may obviously be mounted on the rim, lid, or receptacle, as for example pivoted wire lever like formations.

65 By dishing a lid's top, I may make my rims as deep as I choose, and consequently

efficiently apply the invention no matter how near the receptacle's grip is to the level of the receptacle's top.

To prevent accidental release, lateral rim play, and act as lid registers, I may further 70 use shapes, indentations, bosses, or locks, or any other suitable means on a lid (or rim) or receptacle or both, so shaped and disposed as would obviously meet these requirements, as for example:—rim indent or locks touching a receptacle's throat serve these three objects; external receptacle or rim protuberances can shield the rim's clearance positions from blows; projection or locks thereon may be caused to too deeply engage the 80 receptacle to be released by the external rim's pressure deformation to act as transit locks for violent handling, or indicate tampering, such being freed by attached loops, 85 or tongues, or prising outwards; spot soldering of the rim to a metallic receptacle or grip may be alternatively used, or such receptacle arranged to be initially pressed inwards at a lock position. External bulging 90 on a lid's top near a lock may be used to assist the deformation and initial release of a rim, as depressing such bulging causes outward movement of the rim (particularly scalloped rims), and if made non-recoverable to such depression and essentially having to coact with rim pressure for initially opening a closure it will indicate tampering, 95 said bulging for protection being preferably less prominent vertically than other part or parts of the lid's top, and obviously (if recoverably formed) may assist the lid's application and removal.

Suitably placed rim indents or grooving or lid dishing may when desired also retain sealing media.

In releasing bulged and strengthened rims the operative rim release pressure applied to the rim clearance portions need not necessarily be applied normal thereto, but often even vertically thereto, and use may be made of many forms of rim pressing dies or channels to apply or release the stiffer order of rims.

I may use wire and skeleton like forms of 115 rims in accordance with this invention, or lids having wire folded in or suitably attached thereto, in place of, but virtually fulfilling the described functions of the rim or its parts.

The rim or lid may be made of any suitable material, or materials, or any suitable combinations of materials, as for example:—iron, brass, tinplate, aluminium, duralumin, tagger sheet, carton like covers held by (or attached to) a metallic rim.

The lid and rim and receptacle are of any kind which is of a suitable shape or type to conform to the requirements of the invention, which requirements are readily understood from the description and drawings 130

here provided, it being obvious that many unstated innumerable combinations of my herein stated constructive features can be effected without departing from the spirit of this invention. This invention can obviously be used non-hermetically, or as a stopper retainer.

Locks and receptacle's grips (or both) for features 7 and 8 may be placed or formed at 10 varying level or series of levels in a closure, the latter being also most adaptable to pierced or holed closures' orifices which are throttled and opened without completely removing the closure, as for example closures 15 which so operate on turning or partially withdrawing. In one closure I may vary the number, length, position, level, depth of engagement, size, type of locks, or receptacle's grips (or both) often by such means 20 proving features such as 2, 4, 5, 6, 7, 9, 10, 11, 14, 16, 17, 18, 19, and 25, and for feature 5 sometimes employ one or more weak locks, intended to deform even non-recoverably.

Referring to the drawings filed here- 25 with:—

Figure 1, is a perspective view of one form of closure in accordance with this invention, shown partly in section.

Figure 2, is a perspective and part section 30 view of a form of the invention.

Figure 3, is a perspective view of another form of the invention.

Figure 4, is a sectional part elevation of 35 Figure 3.

Figure 5, is a perspective and part section view of another form of the invention.

Figure 6, is a perspective and part section view of another form of the invention.

Figure 7, is a perspective and part section 40 view of another form of the invention.

Figure 8, is a perspective and part section view of another form of the invention.

In each of all of the attached figures, I show one of the many forms of this invention, locks being presumed to have been spaced with due regard to the static considerations aforementioned, and in these figures:—

a is the receptacle, *b* the lid, *c* the rim, *d* 50 *d' d'' d'''* formations minimising the disturbance of the lock's hold, *e* the receptacle's top, *f* the receptacle's grips, *g' g'' g'''* auxiliary receptacle's grips permitting varying "on" positions for the rim or lid (or shallower types of rims), *h* *h'* sealing medium or valve or packing, *j* *j'* general strengthening formations for the closure, *k* *k' k''* locks engaging *f* or *g*, *k'''*, *l* a protuberance on the receptacle, and on the lid *b* being rotated, *l'* 55 may force out the locks, *l''* may impart releasing pressure to the rim's clearance portion, the rim edge when nesting in the groove *l'''* is restricted in movement, *m* *m' m'' m'''* formations tending to control (or regulate) 60 rim or lid arching between the locks for

safety valve action, *n* *n' n'' n'''* formations tending to concentrate or uni-directionalise the rim's release action towards the direction *o*, *p* *p' p''* preventors of rim disturbance, by contact with the receptacle, *q* *q'* retainers of sealing medium or packing, *r* *r'* and *r'' r'''* respectively showing closely defined and approximate positions where the described rim pressure or squeezing for the rim's release should be applied, *s* *s'* clearance positions for the rim to yield inwardly, *t* formations for securing tighter seal.

In all drawings, the locks are presumed to have been proportioned or spaced commensurate with the pressure of sealing, rim 75 strength, and extent of lid or rim yield for condition or feature 5.

Figure 1, shows a sheet metal lid, the unseen side being of the same form as the side illustrated; the lock *k'* beginning at *k'* and extending round the rim edge to *k''*, is slightly longer than the opposite lock *k*, and by being stiffer and longer concentrates release motion towards *o*, the lock *k* having some recoverable yield for feature 5. *d*, *p*, *q'* and *u*, *m'''* are indents, the latter forming an auxiliary engagement. *m'''* and *m'* are cuts. *d*, *d'''*, *j*, *m*, *n'*, *p''* and *q* and the embossed arrows and words are optionally raised or recessed metal. *h'* is optional. 90 The receptacle's body is shown projecting beyond the closure for feature 14, and as a fulcrum assists prising out of a lock. The remaining function of *l*, *l'*, *l''*, *l'''*, is already 95 described. This closure suits features 1 to 26 inclusive, except 21 on account of the indents. The separately marked grips on the receptacle are not screw threads, but re-entrant flanging arranged in tiers.

Figure 2, is a cheap form of the invention applied to a circular tin, the lid being a circular blank, "drawn down" and half false wired all round the rim edge, and flattened by press operation between the points *w* and *w'* and *w''* and *w'''* and thus providing the clearance portions; the two unequal length locks being the un-flattened parts of the half false wire. *f* is an externally and abruptly formed circular channelling made by, and during the same press operation which formed the internal all round false wire at *e*. *h* is a circular disc. This closure suits features:—1, 2, 3, 4, 5, 6, 7, (8 and latter part of 8 on suitable receptacle) 10, 11, 12, 13, 14, 15, 16, 17, 18, 19, (20 partially) 120 21, 22, 23, 24, 25, and 26.

Figures 3 and 4 show a form of this invention applied to a beer bottle, the lid being a pressing dished concavely at *t* to compress *h* firmly on to *e*'s inner edge. The locks, for frequent "on" and "off" application and to withstand high internal receptacle's pressure, have recessed or raised groovings at *d*. The locks being V formed as shown and the V formation is flattened at 125 130

the clearance portions s , s' , k being about half the length of k' . x is a wire attachment threaded through the rim and round the neck of the bottle to prevent loss of the cap. This closure suits features:—1, 2, 5, 6, 7, (8 and the latter part of 8 with suitable receptacle) (9 if desired) 10, 11, 12, 13, 14, 15, 16, 17, 18, (20 partially) 21, 22, 23, 24, 25, and 26.

10 Figure 5, shows the invention applied to a square tin box, the locks being small false wiring, flattened at the clearance portions s , s' (two opposite bulge formations on the rim). Optionally the clearance portions 15 may be obtained in like manner as illustrated and described for Figure 2, or to better obtain feature 14 the bulge is made more pronounced and the false wiring only slightly flattened. h in this case was run into q 's 20 grooving when fluid. The grips f , f' being an all round internal channelling which may be optionally interrupted at the clearance portions s , s' . This closure suits features as mentioned for Figure 2.

25 Figure 6, is a type of closure found suitable for general use; k and k' are upturned rim edge locks preferably crimped as shown by the wavy dotted line. This closure can be made by one press operation and is suitable 30 for features 1 to 26 inclusive (except 8).

Figure 7, shows a form of closure in accordance with this invention, in which h is disposed on the side of the receptacle bedding on the formation t . k and k' being 35 large three quarter false wiring, off set as shown, and of the lengths indicated by the arrows. The clearance portions s , s' are obtained by the shaping of the cut blank so that the false wiring is only barely half 40 formed at these portions, as shown at z , k , and k' being by their liberal formation and off set, springy and of a recoverably yielding nature.

45 Figure 8 is a closure generally as in Figure 6 but with the metal removed at the clearance portions s , s' and a pivoted wire loop substituted as shown. To receive the wires' ends, the locks k and k' are full false wires. To release the closure the loops are 50 brought down to the dotted position and pressed inwards at r'' , r''' . The bottle projection x' on either side of a is formed so that the wires y and y' when brought down can snap over x' and thus function as 55 the well known processing "clips" for automatic vacuum closures. In further reference to Figures 2 and 5 the flattening of the upturned rim edge is not my manner of providing the locking projections, these being 60 already provided before flattening takes place, but on the contrary said flattening is to provide clearances and to eradicate unrequired already formed locking projections, overformed merely for the convenience

of employing circular initial sheet metal 65 blanks.

Reference to all figures will show that sufficient squeezing of the rim edge at the two clearance positions substantially frees both locks simultaneously. I point this out 70 specially because the arrow lines in the direction o might show an intent to merely free but one lock, whereas, as previously stated features 11 and 16 are features which are being improved by the unequal length 75 of locks illustrated.

What I claim and desire to secure by Letters Patent is:—

1. A closure for receptacles comprising a lid provided with a rim, said rim being 80 provided with at least one lock adapted to engage a corresponding receptacle's grip and some extent of said rim simultaneously being adapted to be inwardly deformed sufficiently to result in at least one lock becoming outwardly moved substantially to a 85 position of broken engagement with respect to its coacting said grip.

2. A closure for receptacles comprising a lid provided with a rim, said rim being 90 provided with at least one lock adapted to engage a corresponding receptacle's grip and some extent of said rim simultaneously being adapted to be inwardly deformed sufficient to result in all said rim's operative 95 locking portions becoming outwardly moved to substantially an ineffectual operative locking position with respect to their coacting receptacle's engaging provision.

3. The combination of a receptacle and closure mutually formed and structurally assembled as follows:—said closure comprising a lid having a rim provided with contactual holding provision adapted to have bearing hold with respect to correspondingly disposed contactual holding provision provided on the receptacle's exterior, said hold being peripherally interrupted, and substantially where some such said interrupting ensues some of the external contour of the receptacle and some of the contour of the rim being mutually formed to follow separated paths sufficiently far apart as to be adapted to provide adequate clearance provision for the rim to be inwardly 100 deformed sufficient to occasion at least one arranged peripheral bearing portion of hold of said rim moving outwards to substantially 105 a position of broken engagement relationship with respect to its said co-acting contactual holding provision of the said receptacle.

4. The combination of a receptacle and closure mutually formed and structurally assembled as follows:—said closure comprising a lid having a rim provided with contactual holding provision adapted to have bearing hold with respect to corre- 115 120 125

- spondingly disposed contactual holding provision provided on the receptacle's exterior, said hold being peripherally interrupted, and substantially where some such said interrupting ensues sufficient of the external contour of the receptacle and sufficient of the contour of the rim being mutually formed to follow separated paths sufficiently far apart as to be adapted to provide adequate clearance provision for the rim to be inwardly deformed sufficient to substantially simultaneously occasion enough outward movement of the rim substantially sufficient to so liberate its entire said contactual holding provision with respect to the coacting contactual holding provision of said receptacle as to admit of said rim's instantaneous withdrawal from said receptacle.
5. A closure for receptacles comprising a lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, means for preventing engaging ingress of a lock to be greater extent than the rim's clearance provision is adapted to disengage.
6. A closure for receptacles comprising a lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, at least one lock being formed to be of a shouldering or inclined bearing nature with respect to at least one receptacle's grip.
7. A closure for receptacles comprising a lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, means being simultaneously provided whereby the closure has substantially fixed lateral stability coincident with its holding provision properly and readily engaging.
8. A closure for receptacles comprising a lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, and means for strengthening the engaging hold of said closure with respect to its receptacle.
9. A closure for receptacles comprising a lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, a suitably disposed substantially smooth substantially direct traversing course being provided over the receptacle's periphery down to the level of at least one receptacle's grip and optionally peripherally sufficient to entail expanding of the rim's locking formation outwards to traverse the said course.
10. A closure for receptacles comprising a lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, some of said receptacle's gripping surface, provided to coact with at least one rim lock, comprising shouldering or the like formed to proceed for some distance around the receptacle's exterior substantially as an engaging contour of uniform positioning as measured from the plane of said receptacle's orifice.
11. A closure for receptacles comprising a lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, at least one coacting gripping formation in the combined assembly of the closure and the receptacle being formed substantially as an "all round" gripping member.
12. A closure for receptacles comprising a lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, and a receptacle formed (in the neighbourhood adapted to

grip the said closure) to have uniform transverse wall cross section at all peripheral positions.

13. A closure for receptacles comprising a lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, and said receptacle's grip being the underside of shoulder-
ing or the like provided on said receptacle's exterior.

14. A closure for receptacles comprising a

lid provided with a rim, said rim being provided with at least one lock adapted to engage a corresponding receptacle's grip and some extent of said rim simultaneously being adapted to be inwardly deformed sufficient to result in at least one lock becoming outwardly moved substantially to a position of broken engagement with respect to its coacting said grip, said lock comprising an inwardly directed portion of said rim's lower edge of substantially symmetrical formation along its total engaging peripheral span.

In testimony whereof I have signed my name to this specification.

ROBERT STANLEY BROWN.
